(57) CLAIM

The ornamental design for a purse, as shown and described.

DESCRIPTION

FIG. 1 is a front perspective view of a purse showing our new design;

FIG. 2 is a right side view, the left side being a mirror image thereof;

FIG. 3 is a front side view thereof;

FIG. 4 is a top view thereof; and,

FIG. 5 is a bottom view thereof.

The strap is shown broken away in the views to indicate indeterminate length.

1 Claim, 2 Drawing Sheets
